US00D631960S

(12) **United States Design Patent**
Myers

(10) **Patent No.:** US D631,960 S
(45) **Date of Patent:** ** Feb. 1, 2011

(54) **HANDGRIP FOR TATTOO MACHINE**

(76) Inventor: **Todd Brandon Myers**, 1530 N. Elk Grove Ave., Unit J, Chicago, IL (US) 60622

(**) Term: **14 Years**

(21) Appl. No.: **29/348,131**

(22) Filed: **Dec. 1, 2009**

(51) **LOC (9) Cl.** 24-02

(52) **U.S. Cl.** D24/133; D24/146

(58) **Field of Classification Search** ..... D24/133, D24/134, 135, 136, 137, 138, 139, 140, 141, D24/142, 143, 146, 150, 152, 144, 145, 147, D24/148, 149, 151, 153, 154, 127, 128, 129, D24/130, 107-108, 112, 111, 200; D8/40, D8/47, 57, 60, 67, 68, 69, 80, 82, 83, 84, D8/93, 94, 97, 107, 72, 73, 74; 600/184, 600/201-203, 210-218, 220-223, 224, 225-227; 606/7, 86 A, 86 B, 119, 129, 18; 81/9.22; 604/48

(57) **CLAIM**

The ornamental design for handgrip for tattoo machine, as shown and described.

DESCRIPTION

FIG. 1 is a top plan view of the handgrip for tattoo machine of the claimed design;

FIG. 2 is a bottom plan view of the handgrip for tattoo machine;

FIG. 3 is a front view of the handgrip for tattoo machine;

FIG. 4 is a rear view of the handgrip for tattoo machine;

FIG. 5 is a left side view of the handgrip for tattoo machine;

FIG. 6 is a right side view of the handgrip for tattoo machine;

FIG. 7 is a top/left/front perspective view of the handgrip for tattoo machine;

FIG. 8 is a top/right/front perspective view of the handgrip for tattoo machine;

FIG. 9 is a bottom/left/rear perspective view of the handgrip for tattoo machine;

FIG. 10 is a bottom/right/rear perspective view of the handgrip for tattoo machine; and,

FIG. 11 is a front view of the handgrip for tattoo machine shown in a use state.

The broken line circles and curves shown in FIGS. 1, 2, 4, 7, 8, 9 and 10 that are immediately adjacent the claimed areas represent the bounds of the claimed design while all other broken lines including the connection tube, the tip and the illustration of a human hand are directed to environment and are for illustrative purposes only; the broken lines form no part of the claimed design.
